DRESS SHIELD

Le Roy Eisenberg, Flushing, N. Y., assignor to
 I. B. Kleinert Rubber Company, New York,
 N. Y., a corporation of New York

Application June 21, 1937, Serial No. 149,330

3 Claims. (Cl. 2—53)

This invention relates to dress shields. Dress shield manufacturers who guarantee the protective qualities of their shields require as a condition of the guarantee that the users sew the dress shields to the garment in a specified way as for example, at five or more points of each flap of the shield. It is well known, however, that in order to eliminate the necessity for sewing the shields in the garments, many women attach the shields by means of safety pins, one at each of the upper points of the shield and one at the center of the bottom edge of each flap. When shields are thus attached by safety pins, they have a tendency to curl in such manner that the protective area of the shields is reduced to a triangular section substantially equivalent to that formed by lines extending from each of the upper points of the shield to the point at the center of the bottom of the flap which is attached to the garment. Shields which are thus attached to the garment so that they curl as just described and thereby reduce the protective area are not guaranteed by the manufacturer.

One object of the present invention, therefore, is to provide a dress shield which, although fastened to the garment by safety pins in the manner hereinbefore described will, nevertheless, afford proper protection.

Another object of the invention is to provide a dress shield with improved means for facilitating the attachment thereof to the garment.

Yet another object of the invention is generally to improve the construction of dress shields and to facilitate the attachment thereof to the garment.

The above objects of the invention will be fully understood from the following description considered with reference to the accompanying drawing which shows the preferred embodiment of the invention.

In the drawing:

Fig. 1 is a side view of a dress shield embodying the present invention;

Fig. 2 is an enlarged sectional view on the line 45 2—2 of Fig. 1;

Fig. 3 is an enlarged sectional view on the line 3—3 of Fig. 1.

Referring now more particularly to the drawing, the dress shield made in accordance with the present invention comprises, as usual two sections 1 and 2 having an upper concave edge 3. Said sections are united at said edge and are otherwise separable. Section 1, as here shown, is larger than section 2 and is intended to be positioned adjacent the body while section 2 is in-

tended to be positioned adjacent the arm. Said sections comprise two crescent shaped flaps 10 and 12 made of rubber or rubber compounds or of any other suitable water-proof material and attached at their upper concave edges 14 in the usual manner as by a cut-seaming operation when said flaps are made of rubber or certain rubber compounds. Flaps 10 and 12 are disposed between cloth flaps comprising layers 16—18 and cloth flaps comprising layers 20—22, respectively. Flap layers 18 and 22 are stitched together at the upper concave edge of the shield by a line of stitching 24, and flap layers 16 and 20 are folded outwardly to provide a tab 26 disposed between shield sections 1 and 2 adjacent the upper concave edge thereof for the full length of the latter. Said tab is stitched at its upper edge by a line of stitching 28 and at its lower edge by a line of over-edge zig-zag stitching 30. The outer edges of companion cloth flap layers 16—18 and 20—22, are stitched by lines of over-edge zig-zag stitching 32 and 34 respectively.

The cloth flaps instead of being substantially co-extensive with the water-proof flaps, as heretofore, are extended beyond the lower edges of said water-proof flaps. Thus, as illustrated in the drawing, the cloth flaps have lower portions 36 and 38 which extend beyond the lower edges 40 and 42, respectively, of their companion water-proof flaps. As clearly shown in the drawing, the cloth flap of each section has convexly curved side edges extending from the opposite ends, respectively, of concave edge 3 along converging lines throughout their extent to the tips of said sections whereby said sections are approximately triangular, so that when said sections are pinned to the garment at said tips and at the opposite ends of said concave edge the lines of pull between the tips and said ends are sufficiently close to said convexly curved edges, respectively, to prevent substantially curling of the sections of the shield. The dress shield of this construction may be attached to the garment by safety pins, one at each upper point at the side edges of the shield and one at each central point at the bottom edge of each flap, and when so attached afford adequate protection as the flaps do not curl. Furthermore, the extended flap portions facilitate the fastening of the safety pins or other fasteners therefrom because of the absence of the water-proof material in these portions of the shield. The attachment of the safety pins at the upper points of the shield is facilitated by the provision of the tab 26 which permits the ready and convenient attachment of the safety pins thereto.

instead of through the water-proof flaps or through special tabs as heretofore sometimes provided with the view of facilitating the attachment of the dress shields to the garments.

5 Thus it is seen that the dress shield herein shown and described is well adapted to accomplish the several objects of the present invention. It will be understood, however, that certain changes in the construction and arrangement of 10 parts may be made in the dress shield herein specifically shown and described. Therefore, I do not wish to be limited precisely to the present construction, except as may be required by the appended claims considered with reference to 15 the prior art.

Having thus described my invention, what I claim and desire to secure by Letters Patent is:

1. A garment shield of the kind described having an upper concave edge and comprising two 20 sections united at said concave edge and otherwise separable from each other, each of said sections including an inner waterproof flap and an outer cloth flap, each cloth flap of said two sections comprising opposed layers between which 25 the companion waterproof flap is disposed and thereby covered, said opposed layers of the cloth flap of one of said sections extending beyond the lower edge of its companion waterproof flap to provide for pinning the lower tip of the former 30 above its lower edge without penetration of the waterproof flap by the pin, said last mentioned cloth flap having convexly curved side edges extending from the opposite ends, respectively, of said concave edge along converging lines throughout their extent to said tip thereof whereby said 35 last mentioned section is approximately triangular so that when it is pinned to the garment at said tip and at the opposite ends of said concave edge the lines of pull between the tip and said 40 ends are sufficiently close to said convexly curved edges, respectively, to prevent substantially curling 45 of said last mentioned section.

2. A garment shield of the kind described having an upper concave edge and comprising two 45 sections united at said concave edge and otherwise separable from each other, each of said sections including an inner waterproof flap and an outer cloth flap, each cloth flap of said two sections comprising opposed layers between which 50 the companion waterproof flap is disposed and thereby covered, one of said sections being substantially longer than the other, the opposed layers of the cloth flaps of each of said sections extending beyond the lower edge of its companion waterproof flap to provide for pinning the lower tips of the cloth flaps above their lower 55 edges without penetration of the waterproof flaps by the pins, each of said cloth flaps having convexly curved side edges extending from the opposite ends, respectively, of said concave edge along converging lines throughout their extent to said 60 tips whereby each of said sections is approximately triangular so that when it is pinned to the garment at said tip and at the opposite ends of said concave edge the lines of pull between the tip and said ends are sufficiently close to said convexly curved edges, respectively, to prevent substantially curling of said flaps, the opposed layers of said cloth flaps being stitched together at said convexly curved edges thereof and to the adjacent edges of the companion waterproof flap except at said portion of the flap which extends beyond the waterproof flap.

LE ROY EISENBERG.

ing beyond the lower edge of its companion waterproof flap to provide for pinning the lower tip of the former above its lower edge without penetration of the waterproof flap by the pin, said last mentioned cloth flap having convexly 5 curved side edges extending from the opposite ends, respectively, of said concave edge along converging lines throughout their extent to said tip thereof whereby said last mentioned section is approximately triangular so that when it is 10 pinned to the garment at said tip and at the opposite ends of said concave edge the lines of pull between the tip and said ends are sufficiently close to said convexly curved edges, respectively, to prevent substantially curling of said last mentioned section, the opposed layers of said cloth flaps being stitched together at said convexly curved edges thereof throughout their extent and to the adjacent edges of the companion waterproof flap except at said portion of the flap which 15 extends beyond the waterproof flap.

3. A garment shield of the kind described having an upper concave edge and comprising two sections united at said concave edge and otherwise separable from each other, each of said 20 sections including an inner waterproof flap and an outer cloth flap, each cloth flap of said two sections comprising opposed layers between which the companion waterproof flap is disposed and thereby covered, one of said sections being substantially longer than the other, the opposed layers of the cloth flaps of each of said sections 25 extending beyond the lower edge of its companion waterproof flap to provide for pinning the lower tips of the cloth flaps above their lower 30 edges without penetration of the waterproof flaps by the pins, each of said cloth flaps having convexly curved side edges extending from the opposite ends, respectively, of said concave edge along converging lines throughout their extent to said 35 tips whereby each of said sections is approximately triangular so that when it is pinned to the garment at said tip and at the opposite ends of said concave edge the lines of pull between the tip and said 40 ends are sufficiently close to said convexly curved edges, respectively, to prevent substantially curling of said flaps, the opposed layers of said cloth flaps being stitched together 45 at said convexly curved edges thereof and to the adjacent edges of the companion waterproof flap except at said portion of the flap which extends 50 beyond the waterproof flap.
